UNITED STATES PATENT OFFICE

2,567,234

MACHINE FOR COATING INSOLE BLANKS

Harry Phillips, Beverly, Mass., assignor to United Shoe Machinery Corporation, Flemington, N. J., a corporation of New Jersey

Application December 15, 1948, Serial No. 65,325

11 Claims. (Cl. 91—51)

1 This invention relates to machines for coating pieces of relatively thin material and is herein illustrated as embodied in a machine for applying a coating of adhesive, hereinafter termed cement, to the whole of one face of an insole blank.

In the making of many insoles it is desired to adhesively secure a reinforcing canvas to an insole blank, which is sometimes made of wood fibre and sometimes of leather, in order to give it greater strength. For reasons of economy these insole blanks are sometimes quite thin and flexible and it is impossible to apply a satisfactory coating of cement to them by utilizing the well-known sole-cementer in which a presser roll is employed to hold the work in contact with the applying roll because of the danger of the transfer of cement to the presser roll from which it will be later transferred to the clean surface of pieces of work. The general problem of avoiding this difficulty while coating thin material was solved in a machine which is illustrated in Letters Patent of the United States No. 2,318,600, granted May 11, 1943, upon the application of P. H. Dixon, in which the machine has a pair of coating feed rolls in advance of the applying roll and arranged to present the end of the incoming work to the upgoing side of the applying roll near the top thereof. The resistance of the work to bending is effective to hold it in firm contact with the applying roll. The angular arrangement of the plane of the axes of these feed rolls may be varied in accordance with the particular work to be treated and furthermore the grip on the work and the minimum spacing of the feed rolls may be adjusted.

With some types of material a satisfactory coating of cement can be applied by means of a roll traveling in the same direction as the work; in other cases, where a heavier coating is desired, it is found preferable to reverse the rotation of the applying roll so that it is rubbed across the under surface of the work as it is moved positively forward by the feed rolls. The quantity of cement carried up to the insole by the applying roll is usually determined by a stripper associated with the upgoing side of the roll. With solvent-cut rubber cement, such a stripper may comprise a plate or a bar, but when latex cements are used it is preferable or necessary to employ a driven roll for stripping or controlling the quantity of cement carried to the insole by the applying roll. It will be readily understood that when the direction of rotation of the applying roll is reversed the position of the stripper must be also changed from one side to the other of the applying roll.

Accordingly, one object of the invention is to

2 provide an improved machine of the above type in which provision is made for easier adjustment of the feed rolls.

To that end, and in accordance with a feature of the invention, the two feed rolls are mounted in a tiltable carrier the position of which may be readily adjusted without interfering with the drive of the rolls. Combined with this arrangement is a provision for adjusting the spacing of the rolls and the tension of the spring which urges them together.

Still another feature of the invention resides in an improved arrangement for supporting the stripper which, while avoiding extreme niceties of machine work, permits exact positioning thereof at either side of an applying roll. To that end, the illustrated arrangement includes a stripper carried by arms which are clamped to a pivot rod. After the adjacent faces of the stripper and applying roll have been set parallel, clamping of the arms to the pivot rod is effected by draw bolts, thus maintaining their parallelism throughout adjustment of the stripper by swinging its support on the pivot rod.

25 Other features of the invention relate to the support of the cage for a bottle which is used for a barometric feed to an open tray carrying the cement to the underside of the applying roll. A novel arrangement for supporting the cage is such that it may be tilted to an inoperative position with the supply bottle above the edges of the tray, to facilitate removal of the latter.

30 These and other features of the invention will be best understood from a consideration of the following specification and accompanying drawings, in which:

35 Fig. 1 is a plan view of a machine embodying the present invention, parts being removed and broken away to show the applying roll arranged to be driven in a direction opposite to the direction of movement of the work;

Fig. 2 is a similar view, with the drive of the applying roll reversed;

40 Fig. 3 is a side elevation of the delivery end of the machine, the rolls being arranged as in Fig. 2;

Fig. 4 is a fragmentary view of the feed roll carrier;

Fig. 5 is a front elevation;

45 Fig. 6 is a detail in plan of the mounting for the applying roll and its stripper roll, with parts in section on the line VI—VI of Fig. 5;

Fig. 7 is a detail view showing a pivot stud for the applying roll, taken partly in section on the line VII—VII of Fig. 5;

Fig. 8 is a vertical section through the operating rolls taken on the line VIII—VIII of Fig. 2;

Fig. 9 is a fragmentary vertical section on the line IX—IX of Fig. 2; and

Fig. 10 is a similar section on the line X—X of Fig. 1.

The machine comprises a frame 10 (Fig. 3) supported upon legs 12 and provided with a back flange 14 (Figs. 1 and 8) which interconnects an end flange 16 (Fig. 3) and a gear box 18. This box is provided with a removable cover 20 and has a forward extension 22 for a purpose which will later appear.

The operating parts of the machine include an applying roll 24 (Fig. 8), a stripper here shown as a roll 26, and feed rolls 28 and 30. These rolls are all driven, and their arrangement is such that an operator facing the front of the machine (Fig. 5) presents with his right hand the end of an insole blank, for example, to the right side of the feed rolls which carry it against and then over the top of the applying roll to receive a coating of cement on the under surface thereof, after which the operator grasps the edges of the insole with his left hand, and places it in a rack (not shown) for drying.

Assisting in the presentation of the work is an inclined trough-like table 32 (Figs. 5 and 8) which is carried by a pivot 34 positioned at the upper end of a bracket 36 which is clamped against a key 38 on the back flange 14 of the frame and is held there by a screw 40. The screw passes through a slot 42 in the bracket to permit vertical adjustment thereof, and the bracket has an extension 44 in which is threaded a set screw 45 for adjustably clamping a post 46 pivotally connected to the underside of the table. By this arrangement, the height and inclination of the table may be varied to suit the needs of the particular work or the habits of the operator.

The underside of the applying roll dips in a coating material, such as latex, contained in a tray 50. One portion of this tray (Fig. 5) rests upon the frame extension 22 and is clamped thereagainst by a swinging bolt 52 associated with forked lugs on the tray. A cover plate 54 having an upstanding flange 56 is used to keep any foreign matter out of the tray as well as to catch the work if it accidentally drops before the operator grasps it. At its remote end, the tray is provided with a cup-like portion 58 (Fig. 3) above which is a cage 60 for an inverted bottle having at its mouth 62 a valve 64 of the type shown in the U. S. Letters Patent 2,013,853, granted September 10, 1935, upon the application of E. J. Ray. By this means the level of the liquid in the tray is kept substantially constant.

In order to facilitate the removal of the tray for cleaning, the cage 60 is secured to a block 66 by means of a screw 68 (Figs. 1 and 5) passing through a slot 69 in the block. This block is pivoted for tilting movement about a screw stud 70 threaded in the gear box 18. The normal vertical position of the block is determined by a hook-like flange 73 upon a plate 72 which is attached by screws to the gear box 18 between it and the tilttable block 66. This plate 72 has a recess 74 cooperating with a spring stud 76 which holds the block and the cage in a tilted position indicated in broken lines in Fig. 3, thus raising the end of the bottle above the level of the tray to permit the easy removal of the latter when the clamp bolt 52 is released.

The applying roll 24, the surface of which may be either smooth or rough, has gudgeons 80 and

82 (Fig. 1). The gudgeon 80 (Fig. 7) is provided with a conical recess to receive the yieldably mounted pivot stud 84 which has a flange 86 on its inner end and is hollow to receive a spring 88 which urges the pivot stud toward the gudgeon. A cover plate 90 attached by screws to the frame holds the spring in position and is provided with an inturned lip 92 which engages a notch in the flange 86 of the pivot stud to prevent the latter from turning with the roll.

The other gudgeon 82 is coupled at 94 (Fig. 1) to an enlargement at the end of a driven shaft 96 journaled in the gear box and connected by gears 98 and 100 to a shaft 102 joined by miter gears 104 to a drive shaft 106 on which there are mounted fast and loose pulleys 108 and 110.

This shaft is driven by a belt 112 which may be moved from one pulley to another by means of a shifter fork 114 (Fig. 2) clamped to a peripheral flange 116 on a disk-shaped member 118

hanging from a pivot 120 carried in lugs on top of a housing 122. The flange 116 extends around the circumference of the member 118 thus allowing the belt to be led in at any desired angle. A swinging movement of the belt shifter member 118 is obtained by means of a crank 124 upon the end of a rod 126 which is journaled in a bracket 128 attached to the housing 122.

At the front of the machine this rod 126 is provided with a handle 130 and it will be seen from Fig. 5 that the crank 124 cooperates with a slot 132 in a flange 134 formed upon the member 118. When the handle 130 is in the position shown in Fig. 5, the belt shifter member 118 is

held in its outer position where the belt 112 encircles the idler pulley. A counterclockwise movement of this handle 130 moves the belt shifter inwardly to transfer the belt to the pulley 108 which is fast upon the drive shaft 106. Inasmuch as the crank 124 rests at the bottom of the slot 132 in either extreme position of the handle, it functions to lock the belt shifter in one position or the other without any effort on the part of the operator.

In the arrangement shown in Figs. 1 and 10, the applying roll is so rotated that its upper surface moves in a direction opposite to the direction of movement of the work W as the latter is pushed along by the feed rolls 28 and 30. This is done where it is desired to apply a large quantity of cement. If, on the other hand, a lesser amount of cement is desired, then a driving arrangement shown in Figs. 2 and 9 will be utilized in which an idler gear 132 is interposed between a gear 98' upon the shaft 96 and a gear 100' upon the shaft 102.

The control of the quantity of cement carried by the applying roll to the work is effected by means of the stripper roll 26, having gudgeons 136, 138. This roll is mounted in a U-shaped carrier comprising arms 140, 142 (Fig. 3) clamped on a pivot rod 144 journaled in the gear box 18 and the end flange 16. It is essential that the surface of the stripper roll should be exactly parallel to the surface of the applying roll and, hence, to avoid extreme niceties of machine work, it has been found more practical to clamp the arms 140, 142 separately on the pivot rod by means of draw bolts 146 (Fig. 8) which grip the rod 144 at any point on its circumference and this is done after the stripper roll has been moved into contact with the applying roll. The assembly is then positioned to adjust the quantity of cement on the applying roll

by swinging the U-shaped carrier for the stripper roll about the axis of the pivot rod 144.

As may be seen from Fig. 1, the inner gudgeon 136 of the stripper roll is provided with a coupling 148 to a stub shaft 150 which is journaled in the arm 142, and which passes through a slightly larger hole in the wall of the gear box. When the applying roll is being driven counterclockwise with its upper surface moving in a forward direction, as in Fig. 2, the stripper roll is associated with the upgoing side of the applying roll by moving the carrier arms to the position shown in Figs. 5, 8 and 9. Inside this stub shaft 150 is a centering pin 152. The near gudgeon 138 of the stripper roll rotates upon a spring-controlled conical stud 154 like the stud 84 shown in Fig. 7 for supporting the adjacent applying roll. An enlargement, at the upper end of the arm 140, containing the stud 154, is received in an opening 155 in the end plate 16 of the frame.

The stripper roll is driven oppositely to the applying roll and, in the relation shown in Figs. 2 and 8, a gear 156 on the stripper roll shaft and within the gear box 18 meshes with a gear 158 on the shaft 96 which drives the applying roll. These gears are shown in dotted lines in Fig. 9. If the arrangement of the stripper roll is that shown in Fig. 1 then the gear 156 on the stripper roll shaft meshes with the opposite side of the gear 158 on the shaft that drives the applying roll, as shown in Fig. 10.

Adjustment of the position of the U-shaped stripper carrier, with its arms 140, 142, is effected by means of a bar 160 (Figs. 5 and 6) which is connected to the arm 140 by means of a screw stud 162 and is provided with a reduced portion, surrounded by a spring 154, and has a still further reduced portion 166 extending through the back flange 14 of the frame and on which there is an adjusting nut 168. In order that the same adjusting bar 160 may be utilized in both positions of the stripper roll, the arm 140 is provided with similar, oppositely extending, lugs 170 (Fig. 5) and 172 (Fig. 3). It will be understood that this reversal of the position of the stripper roll may not be effected without moving the stub shaft 150 (Fig. 1) from one position to another in the gear box, and that when this is to be done, the stripper roll is removed by depressing its conical stud 154 and separating the coupling 148.

It will be noted from Figs. 5 and 6 that an extension of the screw stud 162, which connects the adjuster 160 to the ram 140, projects into a slot 174 in the end frame 16 of the machine and opposite ends of this slot are so positioned as to serve as stops, each to limit the movement of the stripper roll toward the applying roll. The lefthand end of the slot serves for this purpose in the arrangement in Fig. 5 where the applying roll is driven counterclockwise, and the other end of the slot serves a similar purpose when the roll is driven clockwise as in Fig. 2.

Presentation of the insole blanks to the applying roll 24 is effected, as noted above, by the coacting feed rolls 28 and 30. Inasmuch as the thickness of the sheet material used for such blanks varies considerably so that some are very limp and others are relatively stiff, it becomes desirable to arrange these feed rolls in such a way that the angle of the presentation of the work may be varied. To this end, a feed roll carrier 180 is made up of a cross bar 182 (Fig. 8) joining two end plates 184 and 186 (Fig. 4). The first of these is recessed at 188 adjacent to the gear box to provide space for driving gears, and

the carrier as a whole is tiltable on the shaft 102 which serves also as a support for the lower feed roll 28. Thus the position of the axis of the lower roll 28 with respect to the axis of the applying roll 24 is unchanged by tilting movements of the carrier 180.

A clamp screw 190 is provided to hold the carrier in adjusted position and this screw extends through an arcuate slot 192 (Fig. 5) in the end plate 16 of the main frame. The upper feed roll 30 is carried upon a shaft 194 which extends between the arms of a yoke 196 (Figs. 4 and 8), said yoke being tiltably mounted in the carrier 180 by means of a shaft 197 journaled in the end members of the carrier and held endwise of such yoke by set screws. Tilting movement of the yoke carrying this upper roll 30 is permitted by an arcuate slot 198 in the end plate 184, and the upper roll is pressed toward the lower roll, 20 to grip the work, by means of a spring 200.

Thus a forwardly tilted position of the carrier is used when limp pieces are to be coated, so as to hold them more firmly in contact with the cement roll and to insure that all of the surface 25 of the work will be coated. When the work pieces are stiffer, the carrier may be tilted to the right where the feed rolls are more nearly above one another. It is also possible to control the feeding of pieces which are not of equal thickness across their width, by tilting the rolls forwardly thereby to twist the pieces into firm contact.

This spring 200 is mounted upon an extension of a screw 202 threaded in a split lug 204 which is provided with a clamp screw 206 so that after 30 the position of the screw 202 has been adjusted, it may be clamped in position. The screw 202 is provided with an abutment 208 against which an upstanding arm 210 upon the yoke 196 rests. The arm is bifurcated to receive the extension 40 of the screw and the spring 200 bears against a washer resting against the other face of the arm 210. The tension of this spring may be independently adjusted by a nut 212 which is held in adjusted position by a lock nut 214. A cover 45 216 hinged upon a cross bar 218 extending between the sides of the table 32 rests against the upper side of the cross bar 182 of the carrier regardless of the adjusted position of the latter and prevents the operator from getting his fingers 50 between the feed rolls.

As was noted above, the lower feed roll 28 is secured to the driven shaft 102 and in order that the upper feed roll may be driven in any position of the yoke with respect to the carrier or in any position of the carrier with respect to the applying roll, a driving arrangement shown 55 in Figs. 9 and 10 is utilized from which it is evident that the pinions are located in a recess 188 of the end plate 184 of the carrier. Starting with the driven shaft 102, it will be seen that a pinion 220 thereon meshes with an idler 222 on a stub shaft 223 carried in the end plate 184, which idler 222 turns another idler 224 loose upon the pivot shaft 197 of the yoke. This last 60 idler 224 serves to drive a pinion 226 upon the shaft 194 of the upper feed roll and, since the movement of the yoke is around the center of the shaft 197, the meshing of the latter two pinions is not disturbed by any movement of the yoke and, hence, of the upper feed roll 30.

With some kinds of insole blanks, there is a tendency of the trailing end to tip up after it leaves the feed rolls and before the whole end or heel area has been coated by the applying roll. This difficulty is avoided by the action of a presser

plate 230 which is secured to the cross bar 182 of the carrier by screws extending through vertical slots in the presser plate and which thus can be adjusted into the best position for preventing the tilting action just described.

In operating the machine it will first be decided whether it is desired to employ the arrangement shown in Fig. 1, where the top of the applying roll 24 moves oppositely to the surface of the work W, or the arrangement shown in Fig. 2, where it moves with the work. Having reached that decision, the driving gears in the gear box 18 will be set up in one or the other of these illustrated arrangements and the stripper roll 26 and its U-shaped carrier will be positioned accordingly so that the stripper roll cooperates with the upgoing side of the applying roll and either lug 170 or 172 on the carrier arm 140 is connected to the adjuster 160. Then the feed roll carrier will be adjusted by means of the clamp screw 190 so as to direct the work downwardly more or less, against the surface of the applying roll to cause it to hug the upper surface of the applying roll thereby to receive a complete and uniform coating. The degree of tipping of the feed roll carrier will depend largely upon the thickness and flexibility of the work.

The position of the abutment 208, by means of which the approach of the upper feed roll to the lower feed roll is determined will be reset if necessary; also, the tension of the spring 200 may be adjusted. The tilt of the table 232 having been set for greatest convenience in accordance with the particular work, the operator will hold an insole blank in the right hand and slide it down the table until it reaches the bite of the feed rolls which will carry it into contact with the applying roll and thence under the plate 230, and when it projects far enough, it will be grasped by its periphery in the operator's left hand and transferred to a drying rack.

When removing the tray 50 for any desired purpose, after loosening the clamp bolt 52 therefore, the bottle cage 60 will be tilted to the inclined position shown in Fig. 3 where it will be held by the engagement of the friction pin 76 in the recess 74. When the tray has been replaced in its position the cage may be tilted back until the block 66 to which it is attached engages the flange 73 on the small plate 72. It will then be in operating position ready for use.

Having thus described my invention, what I claim as new and desire to secure by Letters Patent of the United States is:

1. In combination, a coating-applying roll, means for supplying coating material to that roll, a tiltable carrier adjacent to said applying roll, feed rolls in said carrier coacting to grip a piece of work, said carrier being tiltable about the axis of one feed roll, means for clamping the carrier in any of a plurality of angularly related operating positions, thereby to determine the angle of presentation of the work to the applying roll, by said feed rolls, and means for driving said feed rolls in any operating position.

2. In combination, a coating-applying roll, means for supplying coating material to that roll, a tiltable carrier adjacent to said applying roll, coacting feed rolls in said carrier, spring means for pressing one of said rolls against a piece of work resting on the other roll, means for clamping the carrier in any one of a plurality of operating positions, and means mounted on the carrier for determining the limit of approach of one of said feed rolls to the other.

3. In combination, a coating-applying roll, means for supplying coating material to that roll, a tiltable carrier adjacent to said applying roll, feed rolls on said carrier coacting with opposite sides of a piece of work, means for pressing one of said rolls against the work, means for clamping the carrier in adjusted position, and adjustable means mounted on the carrier for adjustably determining the pressure of said rolls in gripping the work.

4. In combination, a coating-applying roll, means for supplying coating material to that roll, a tiltable carrier adjacent to said applying roll, a pivoted yoke on said carrier, a feed roll mounted in said yoke, another feed roll mounted on said carrier to cooperate with the first feed roll, means for driving said feed rolls in any position, and means mounted on the carrier for adjusting the position of the yoke to determine the minimum spacing between said rolls when no work is present.

5. In combination, a coating-applying roll, means for supplying coating material to that roll, a tiltable carrier adjacent to said applying roll, a pivoted yoke on said carrier, a feed roll mounted in said yoke, another feed roll mounted on said carrier to cooperate with the first feed roll, and a screw threaded in the carrier having an abutment coacting with said yoke for determining the approach of the feed rolls to each other, and having a spring for urging the feed rolls toward each other.

6. In combination, an applying roll, means for carrying a piece of work over said applying roll, means for driving the applying roll, a stripper associated with the upgoing side of said applying roll, means for supporting said stripper comprising a rod supported for turning below the applying roll to move the stripper toward and away from the applying roll, arms on the rod providing bearings for the ends of the stripper, a single device for turning the rod and both arms as a unit, and drawbolts for clamping said arms to said rod in plural positions around its periphery with the adjacent faces of said stripper and said applying roll parallel.

7. In combination, a frame, a driven applying roll therein, means for supplying coating material to the underside of said roll, a U-shaped support pivoted to the frame at the base of the U, a stripper roll removably mounted therein, means connected to the frame for adjusting the U-shaped support, and means for connecting said adjusting means to said stripper-roll-support at either of a plurality of positions, thereby permitting the stripper roll to be positioned on the upgoing side of the applying roll regardless of the direction in which the latter is driven.

8. In combination, a frame having spaced stops, an applying roll on said frame, means for supplying coating material to said applying roll, a stripper roll associated with the upgoing side of the applying roll, a pivoted carrier removably supporting said stripper roll, a rod connected to the frame for adjusting the position of said pivoted carrier, and a member for connecting the adjusting rod to the carrier, said connecting member extending into a position between said stops with the stops positioned to determine the limit of approach of the stripper roll toward opposite sides of the applying roll.

9. In combination, a frame having spaced stops and, a driven applying roll rotatably mounted in said frame, a supply tray beneath said applying roll, a stripper roll adapted to be associated with

the upgoing side of the applying roll regardless of the direction in which the latter is driven, a movable carrier removably supporting said stripper roll, a spring urging said stripper roll carrier toward the applying roll, means connected to the frame for adjusting the position of said carrier, a stud for connecting said adjusting means to the carrier upon opposite sides of the latter, said connecting stud being positioned between and engageable with said stops, the latter serving as limiting means to determine the limit of movement of the stripper roll toward one side or the other of the applying roll.

10. In combination, an applying roll, a tray for supplying coating material to the underside of said roll, an inverted bottle for supplying coating material to said tray and extending below the sides thereof, a valve closing the mouth of the bottle, a pivoted support for said bottle, and friction means for holding said support in a tilted position such that the bottle mouth is then above the sides of the tray. 20

11. In combination, a frame, an applying roll

journaled in said frame, an open tray underlying said applying roll to supply coating material to the underside thereof, a pivoted bottle support on said frame, a bottle supported thereby in inverted position to maintain a constant level in the tray, a valve closing the mouth of the bottle, rigid means for limiting the tilting movement of said support into its normal operating position, and friction means for holding the said support in an inoperative position which facilitates withdrawal of the tray.

HARRY PHILLIPS.
